PLASTIC SHEET MATERIAL OR THE LIKE

Robert D. Becker, Wisconsin Rapids, Wis., assignor to Consoweld Corporation, Wisconsin Rapids, Wis., a corporation of Wisconsin

Filed June 3, 1965, Ser. No. 85,563

Term of patent 14 years

(Cl. D87—3)

FIGURES 1, 2, and 3 together comprise a plan view of a full width of plastic sheet material showing my new design which is repeated regularly in the vertical direction to extend beyond the horizontal dotted lines in all figures; the vertical dot-dash lines at the right in FIGURE 1, both sides of FIGURE 2 and at the left in FIGURE 3 constituting the mating or match lines therebetween.

I claim:

The ornamental design for plastic sheet material or the like, substantially as shown.
